UNITED STATES PATENT OFFICE.

CHARLES R. HARRIS, OF WILLIAMSPORT, PENNSYLVANIA, ASSIGNOR OF
ONE-HALF TO JOSEPH E. AUSTRIAN, OF NEW YORK, N. Y.

SUSPENDERS.

SPECIFICATION forming part of Letters Patent No. 717,989, dated January 6, 1903.

Application filed December 14, 1901. Serial No. 85,943. (No model.)

To all whom it may concern:

Be it known that I, CHARLES R. HARRIS, a citizen of the United States, residing at Williamsport, in the county of Lycoming and State of Pennsylvania, have invented a new and useful Improvement in Suspenders, of which the following is a specification.

My invention relates to an improvement in suspenders.

10 The primary object is to provide a suspender which will automatically adjust or adapt itself to the motions of the body, so that no interference is offered to the perfect freedom of movement of the wearer, in that 15 way rendering them comfortable at all times and under all circumstances.

Another object of nearly equal importance resides in the provision for adjusting the suspenders to the size and form of the wearer, 20 thus making them to all intents and purposes universal in their adaptation, while at the same time insuring strength and efficiency.

Minor objects are to provide a suspender which will be neat and attractive in appearance, popular in design, and strong and durable, as well as lasting in use.

In the accompanying drawings, Figure 1 is a view from the rear of my improved form of suspenders, a portion of the box-back being 30 broken away to show the interior. Fig. 2 is a transverse section of the box-back, and Fig. 3 is a sectional view through the adjusting-loop, Fig. 4 showing a slight modification of this loop.

35 The shoulder-straps A A of the suspenders are of the usual construction and are capable of being lengthened or shortened in the customary manner, this constituting no part of my present invention.

40 Proceeding now to the novel features of my present invention, C indicates the box-back, composed, preferably, of a pair of metal disks suitably separated to afford the required clearance for the back-cord. These disks are 45 connected together at four points equidistant from one another by rounded lugs 1 1, made integral with one or both disks or secured in place rigidly, as the case may be. The manner of connecting these disks is unimportant, 50 and I do not wish to be limited in this respect, as only one of several possible constructions

is illustrated. The main thing is simplicity, economy, and efficiency in this regard, and further attention must be given in the manufacture to the fact that these lugs must be 55 sufficiently rounded to facilitate the sliding action of the cord upon them and to guard against the ends of the lugs cutting into and abrading the cord as it moves through the box-back.

60 D denotes an endless extensible back-cord. This is made in one piece, and, as shown in Fig. 1, it is strung around through the box-back against and inside of the four connecting bearing-lugs. The two upper turns 2 2 65 pass through rigid guides 3 3, depending from the shoulder-straps, wherein they play loosely, and the two lower ends are fastened or joined by metallic clips 4 4' or otherwise, so as to form button-loops 5 5, adapted to button over 70 the rear trousers-buttons, thus rendering the length of the intermediate portion 4^a of the cord unadjustable.

Another feature of my invention to which I desire to draw special attention consists in 75 the wedge-shaped adjusting-loop or auxiliary casing 6, located on clip 4', through which the free or unattached end 7 of the cord is drawn and adjusted and with which it is detachably connected. In this manner the back-cord is 80 shortened or lengthened, as may be required to make the suspenders fit any particular wearer. A single pull upon this end adjusts the length of the two upper turns 2 2 of the cord simultaneously, thus making it a quick 85 and simple operation without altering or shifting the strain, but on the contrary maintaining it always constant and uniform throughout every change or condition. After having thus shortened or lengthened the 90 cord to the size required the surplus cord may be cut off and the extreme end bent into the adjusting-loop or auxiliary casing, the tension brought to bear by the wearer upon the shoulder-straps A A, which transmit the 95 strain to the upper turns 2 2, of which the unattached end 7 is a connected part, causing it to retain this position with greater tenacity as the strain increases. This is the simplest method of adjustment; but it is 100 obvious that other means of accomplishing the lengthening and shortening of the cord

might be employed. For instance, resort might be had to the construction shown in Fig. 4, in which a clamping-lever 8 is pivoted in the loop or auxiliary casing 6 to hold the 5 cord securely after having been adjusted.

From the foregoing it will be observed that the invention affords a wide and adequate range of adjustment in the back, enabling the suspenders to be worn by persons of any 10 build. In short, this suspender can be adjusted to any extent desired, not only avoiding the necessity of running the front buckles high up to be adjust the suspenders, but also allowing the back to be adjusted to fit any 15 individual. A construction of this character and adjustability increases many fold the wearing life of the cords on account of each adjustment of the cord bringing a new wearing-surface through and into contact with 20 the bearing-lugs, these being the only points where cords wear rapidly.

It is needless to say that slight changes might be made in the various parts described without departure from the spirit and scope 25 of my invention, and hence I do not wish to

limit myself to the exact constructions herein set forth; but,

Having fully described my invention, what I claim as new, and desire to secure by Letters Patent, is—

1. The combination with the shoulder-straps of a suspender, and a box-back, of a cord having loose-sliding connection with the straps and box-back, clips uniting the lower ends of the cord to form button-loops, and 35 means connected with one of these clips whereby the length of the cord is adjusted and secured.

2. The combination of shoulder-straps, back and cord, clips secured to the cord so 40 as to form button-loops, one portion of the cord adjustably connected with one of the clips.

In testimony whereof I have signed this specification in the presence of two subscribers. 45

CHAS. R. HARRIS.
